COMBINED DISH STAND AND FOOD WARMER

Jerry E. Wright, Corning, N.Y., assignor to Corning Glass Works, Corning, N.Y., a corporation of New York

Filed June 9, 1961, Ser. No. 65,536

Term of patent 14 years

(Cl. D81—10)

FIG. 1 is a top plan view of a combined dish stand and food warmer embodying my new design.

FIG. 2 is a side elevational view of the same.

FIG. 3 is a sectional view taken on line 3—3 of FIG. 1. I claim:

The ornamental design for a combined dish stand and food warmer, as shown.
